[57] CLAIM

The ornamental design for a computer ribbon reinking system, as shown and described.

DESCRIPTION

FIG. 1 is an exploded front top perspective view of a computer ribbon reinking system showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a top plan view thereof in an in-use state in which the broken line disclosure is shown for environmental purposes only and does not constitute part of the claimed design.

FIG. 1

FIG. 2

FIG. 3

FIG. 4**FIG. 5****FIG. 6**FIG. 7

FIG. 8
